(57) **CLAIM**

The ornamental design for a medical diagnostic kit, as shown and described.

DESCRIPTION

FIG. 1 is a front perspective view of a medical diagnostic kit in accordance with our new design;

FIG. 2 is a front elevation view thereof;

FIG. 3 is a rear elevation view thereof;

FIG. 4 is a side view thereof;

FIG. 5 is a side view thereof, for the side opposite that of FIG. 4;

FIG. 6 is a top view thereof;

FIG. 7 is a bottom view thereof;

FIG. 8 is a rear perspective view thereof;

FIG. 9 is a front perspective view of another medical diagnostic kit in accordance with my new design;

FIG. 10 is a front elevation view thereof;

FIG. 11 is a rear elevation view thereof;

FIG. 12 is a side view thereof;

FIG. 13 is another side view thereof;

FIG. 14 is a top view thereof;

FIG. 15 is a bottom view thereof;

FIG. 16 is a rear perspective view thereof; and,

FIG. 17 is an exploded view thereof.

The stippled shading in the drawings represents surfaces having the contrast in appearance shown.

The broken lines in FIG. 17 illustrate portions of the medical diagnostic kit that form no part of the claimed design.
